(57) **CLAIM**

The ornamental design for a pneumatic tire for heavy vehicle, as shown and described.

DESCRIPTION

FIG. 1 is a front elevational view of a pneumatic tire for heavy vehicle incorporating our new design;

FIG. 2 is a side view of FIG. 1, the opposite side being of identical shape;

FIG. 3 is a front perspective view of FIG. 1; and,

FIG. 4 is an enlarged fragmentary view of FIG. 1.
